LATCH

Original Filed March 27, 1924

Fig. 5.

INVENTOR
Jose Palacios
BY *Roland H. Poland*
ATTORNEY

UNITED STATES PATENT OFFICE.

JOSE PALACIOS, OF NEW YORK, N. Y.

LATCH.

Substitute for application Serial No. 702,301, filed March 27, 1924, abandoned March 18, 1926. This application filed May 18, 1926. Serial No. 108,713.

This invention relates generally to latch locks, having more particular reference to a latch lock comprising a sliding bolt which is retained in engagement with its keeper by hasp and staple elements to which padlocks are adapted to be applied, the invention having for an object the provision of a novel and improved latch lock of this type. This application is a substitute application 10 of one filed by me on March 27, 1924 under Serial No. 702,301.

For further comprehension of the invention, and of the object and advantages thereof, reference will be had to the following 15 description and accompanying drawing, and to the appended claims in which the various novel features of the invention are more particularly set forth.

Fig. 1, of the drawing is a face view showing 20 my improved latch lock applied to a door.

Fig. 2, is a horizontal sectional view taken on the line 2—2 of Fig. 1.

Fig. 3, is a transverse sectional view taken 25 on the line 3—3 of Fig. 1.

Fig. 4, is a fragmentary horizontal sectional view taken on the line 4—4 of Fig. 1.

Fig. 5, is an underside plan view of the 30 rear end of the bolt.

Referring now to the drawing, the reference numerals 10 and 11 indicate portions of a door and door frame respectively, which are secured to the bolt guide and the bolt keeper. The bolt guide, comprises the 35 plate 12, on which the angular guide members 13 are formed, this plate being secured to the door by any suitable fastening elements such as indicated at 14. Slidably mounted on the plate 12, and confined between the guide elements 13, is a block 16 which is formed with the lateral ribs or projections 17, which engage the said guide elements 13. This block is also formed with a longitudinal boring in which is rotatably 40 engaged the bolt 20. The keeper on the door frame comprises the plate 21 secured by the fastening elements 22 to the said frame and having a projection 23 thereon formed with a longitudinal boring 24 to receive the end of the bolt 20 which projects 45 beyond the block 16.

Fixed to, and projecting laterally from, the bolt 20, at the point where the latter emerges from the block 16, is an arm 25 50 which has mounted on its free end a hasp

plate 26 which projects across the edges of the door and the frame and is formed with a number of transverse slots to receive staple elements carried respectively by the door and the frame, there being a pair of end slots 60 28 and a central slot 29 of the staple elements there is a pair 30 arranged to engage in the slots 28 at the ends of the plate 26 and a second pair 31 which are closely adjacent one another when the door is closed 65 and which are adapted to engage in the slot 29 at the center of the said plate, the respective staples of each pair being mounted one on the door and the other on the frame, being here shown as fixed to angular 70 brackets 32 and 33. As shown the staples 31 may be flattened on their adjacent sides to lie in close contact with one another and form in effect a compound staple. A handle 35 is provided on the end of the arm 25 to 75 facilitate swinging movement of the plate 26 on the bolt 20. Forward movement of the bolt may be limited by means of a pin, 37 on the underside of the block which engages in a longitudinal slot 38 in the base 80 plate 12, while rearward movement of the bolt may be limited by means of an upturned lug 39 on the end of the said base plate. To release or apply the bolt the latter is moved longitudinally, and the hasp 85 plate swing to or from engaging position with the staples 30, 31.

To prevent accidental damage to the bolt by swinging the door to closed position with the bolt projected to its forward position 90 I provide a novel retaining element which holds the bolt in retracted position. As here shown a bayonet recess 42 is formed on the underside of a head 43 on the rear end of the bolt which co-operates with the arm 25 in retaining the bolt against longitudinal movement in the block 16. This recess communicates on one side with the rear end of said head and its lateral arm is formed with an inclined wall 42' which is adapted to co-operate with a pin 44 fixed in the plate 12 and projecting thereinto to insure of the bolt being drawn backward to its fullest extent when the handle 35 is released. Surrounding the bolt, adjacent the head 43 95 thereon, is a spring 46 which is fixed at one end of the bolt and at its opposite end to the plate 12 and which normally urges the bolt in a rotary direction to swing the hasp plate 26 downward. When the bolt is 100 105 110

moved backward the pin 44 enters the recess 42 and when the handle is released the bolt turns, under the influence of the spring 46, the pin 44 entering the lateral arm of the recess and locking the bolt in its rearward position.

With my improved bolt a combination bolt and padlock arrangement is provided, while the door can be locked in a position slightly 10 open by arranging the parts with an end slot in the hasp plate 26 engaged with the section of the intermediate staple 31, which is mounted on the door frame.

While I have illustrated and described a 15 preferred embodiment of my invention it is to be understood that I do not limit myself to the precise construction herein shown, and that various changes and modifications might be made therein without departing from the spirit and scope of the invention as defined in the appended claims.

Having thus described my invention, what I claim as new and desire to protect by Letters Patent of the United States, is 25 as follows:—

1. A latch comprising a bolt, a keeper therefor, a block in which said bolt is rotatably mounted, a guide element for said block permitting longitudinal movement of 30 the latter with the bolt, an arm projecting laterally from the bolt, a hasp plate fixed to the free end of said arm and formed with a plurality of slots, said slots being spaced from one another longitudinally of the bolt, 35 and extending transversely with respect to the latter, and staple elements adapted for mounting respectively on a door and door frame and adapted to individually engage the respective slots on the said hasp plate.

40 2. A latch comprising a bolt, a keeper therefor, a block in which said bolt is rotatably mounted, a guide element for said block permitting longitudinal movement of the latter with the bolt, an arm projecting 45 laterally from the bolt, an elongated hasp plate fixed to the free end of said arm and formed with a plurality of slots, said plate

extending parallel to the bolt; and staple elements adapted for mounting respectively on a door and door frame, and adapted to 50 individually engage the respective slots on the said hasp plate said plate having a slot near each end and a central slot said central slot being adapted to receive a compound staple element having one part formed on 55 the door and the other on the door frame.

3. In a latch, a bolt, a keeper element therefor, a block on which said bolt is rotatably mounted, a guide element for said block, a bayonet recess in the said bolt, entered thereinto from the rear end thereof, and a pin on said guide element adapted to enter said recess when the bolt is rotated to hold the bolt in retracted position.

4. In a latch, a bolt, a keeper element 65 therefor, a block in which said bolt is rotatably mounted, a guide element for said block, a bayonet recess in the said bolt, entered thereinto from the rear end thereof, and presenting longitudinal and lateral arms, 70 and a pin on said guide element adapted to enter said recess when the bolt is rotated to hold the bolt in retracted position, and a spring engaged with the bolt and urging it in a direction to cause the said pin to engage in the lateral arm of said recess.

5. In a latch, a bolt, a keeper element therefor, a block in which said bolt is rotatably mounted, a guide element for said block, a bayonet recess in the said bolt, 80 entered thereinto from the rear end thereof, and presenting longitudinal and lateral arms, and a pin on said guide element adapted to enter said recess when the bolt is rotated to hold the bolt in retracted position and a spring engaged with the bolt and urging it in a direction to cause the said pin to engage in the lateral arm of said recess, 85 said lateral arm being a cam wall formed thereon to be engaged by said pin.

In testimony whereof I have affixed my signature.

JOSÉ PALACIOS.
